[57] **CLAIM**

The ornamental design for an icon for a display, as shown
and described.

DESCRIPTION

The single FIGURE view is a front elevational view of an
icon for a display in accordance with our new design.
The broken line drawing of a display is for illustrative
purposes only, and forms no part of the claimed design.
Although the shape of the lightening bolt in the icon is
intended to be illustrated as a zig-zag, the jagged diagonal
lines of the icon are due to the medium used to generate this
FIGURE.
